DESIGN FOR A HAT BOX

Mark W. Cresap, Jr., Philadelphia, Pa., assignor to John B. Stetson Company, Philadelphia, Pa.,
a corporation of Pennsylvania

Application May 1, 1941, Serial No. 100,730

Term of patent 7 years

To all whom it may concern:

Be it known that I, Mark W. Cresap, Jr., a citizen of the United States, residing at Philadelphia, in the State of Pennsylvania, have invented a new, original, and ornamental Design for a Hat Box, of which the following is a specification, reference being had to the accompanying drawing, forming part thereof.

In the drawing:

The rear of the box is the same as the front with the exception that it is without the vertical strap.

The fabric-like finish shown on portions of the box is continued throughout the entire surface of the same, except for the stripes, edges and straps.

I claim:

The ornamental design for a hat box, as shown and described.

MARK W. CRESAP, JR.
